UNITED STATES PATENT OFFICE.

WILLIAM C. ROE, OF PITTSBURGH, PENNSYLVANIA.

FREQUENCY CHANGER.

Application filed November 22, 1919. Serial No. 339,836.

This invention relates to frequency changers, and more particularly to a frequency changer by means of which an alternating current of high frequency may be cut down, or reduced, to a suitable comparatively low frequency for operating bell ringing circuits and for operating any electro-responsive devices which it may be expedient to operate at a lower frequency.

10 Other important objects will hereinafter be made apparent as the description of the invention proceeds.

In describing the invention in detail, reference is herein had to the accompanying 15 drawings, forming a part of this specification, in which similar characters of reference indicate corresponding parts throughout the several views, in which—

Figure 1 is a plan view of certain apparatus embodying my invention positioned in 20 a cabinet;

Figure 2 is a plan view of the cabinet, showing the binding posts for the source of current and the low frequency current;

25 Figure 3 is a diagram of the wiring connections as embodied in my invention, and

Figure 4 is an illustration of a 60 cycle current wave train showing, by shading, the pulsations selected to obtain 20 cycles, using 30 a reed tuned to a natural frequency of 40 cycles.

Referring particularly to Fig. 3, the source of alternating current is supplied at binding posts 1 and 2. A vibrator reed 3 is caused 35 to vibrate continuously by the current passing through a vibrator coil 4 and has an adjusting screw 3^a to which leads a conductor from one of said binding posts, as 2. A suitable condenser 5 and a resistance coil 40 6 are connected in series and shunted across the contacts to prevent sparking at the contact points, and also to insure the opening and closing of the vibrator contacts at substantially zero current, and further creating

45 a continuous and very satisfactory wave for bell ringing apparatus. The transformer 7 is used to obtain the desired voltage and insulate the secondary circuit from the power circuit. It will be noted in the embodiment of my invention herein illustrated

50 that the primary of the transformer has one or more windings adapted to be connected either in multiple or series, as may be necessary, to adapt it to different primary voltages. Also the secondary of the transformer has a winding which may comprise a plu-

rality of sections and which sections may be as indicated adapted to be connected either in multiple or series and attached to terminals so that by using different winding combinations, practically any voltage can be obtained from zero to the transformer maximum; the insertion of a lamp 8 in the transformer primary circuit, is some times advisable to limit the flow of current, although 60 this lamp may be dispensed with where the apparatus is to take care of heavy current demands, the resistance of the lamp may be properly predetermined to limit the current flow of the secondary circuit to a predetermined amount. 65

In operation, although other methods of adjustment may be used, the adjusting screw 3^a of the vibrator can be backed off until the circuit is open and then screwed in until 70 a point is found where the vibrator reed vibrates substantially at its natural frequency period, whereupon it may be substantially sparkless and self starting.

It will be understood that such a reed as 80 illustrated vibrating at 40 cycles per second may thus be adjusted to close the contact for every third positive pulsation and every third negative pulsation, making the frequency 20 cycles through the transformer 85 when the source of current is of 60 cycles frequency.

By referring to the foregoing description and to the drawings, particularly Figs. 1, 3 and 4, it will be seen that current is only 90 supplied to the primary of the transformer 7 whenever the contacts 3—3^a of the vibrator are closed.

Referring particularly to Fig. 4 it will be seen that in the case where a properly adjusted vibrator is employed to convert current abstracted from a 60-cycle source to a current having the operative characteristics of twenty cycles, these contacts 3—3^a are only closed one-third of the time. It follows, therefore, that the reed 3 in its excursions toward the pole face of the electromagnet and receding therefrom will have that excursion which takes place to the left of the indicated position of the reed, Figs. 100 1 and 3, for a period of time which is twice as great as the period of time when the contacts 3—3^a are closed and the reed in the position shown or to the right thereof. In the above reference to the directions right 105 and left, the same is to be taken as viewing the vibrator as shown in Fig. 3. The reed

is adjusted in any of the well-known ways for adjusting reeds to vibrate at a given rate and in its movement from the longer to the shorter excursion it comes up against the end 5 of the contact screw 3^a when traversing the normal position occupied by the reed as illustrated. It is well known that this will have the effect of shortening the reed so far as its rate of travel is concerned, and this effect 10 will be maintained as long as the reed is on that excursion wherein it maintains contact with the contact screw 3^a and presses against it. It is plain from the above also that the reed in making the longer excursion takes 15 twice as long as the making of the shorter excursion, that is, an even multiple of the time consumed in the making of the shorter excursion.

The frequency changer can be well fitted 20 into a cabinet container 10 and have its connections brought to binding posts 1 and 2 for the source of current, and to posts 11, 12 and 13 for the low frequency current on the upper side. Sockets 14 and 15 are provided 25 for the reception of lamps 8 and 9, the latter being located in the power circuit, as shown.

In practice, the electric current, as, for instance, 110 volts, 60 cycles, from the primary 30 source connected to binding posts 1 and 2, traverses a circuit which comprises the conductor leading from post 2, the adjusting screw 3^a to which said conductor is connected, the reed 3, and the frame of the vibrator coil. At this point the current 35 divides, a portion thereof passing to and through the winding of the vibrator coil 4, the lamp 9, and thence to binding post 1, while the other portion passes to and through the primary of the transformer, thence 40 through the lamp 8 to binding post 1. The lamp 9 may have its capacity limited to the extent that just sufficient current is permitted to flow to and through the vibrator winding 4 to keep the reed 3 in vibration, 45 whereas the lamp 8 may be of any capacity required to suit the current desired.

While I have illustrated and described a specific embodiment of my invention, for the purpose of explaining the same, it will be 50 obvious that extensive departures may be made from the specific embodiment herein illustrated and described, without departing from the spirit of my invention whose scope is defined in the appended claims.

Having thus described my invention what 55 I claim as new and desire to secure by Letters Patent of the United States is:

1. In an alternating current system, the combination with a source of alternating 60 current, a current delivery circuit, a reed whose natural periodicity of vibration is different from the periodicity of alternating current from the said source, and operable thereby to vibrate at a rate fractional thereof, current modifying means between the

said source and the said circuit, said reed when so vibrated so controlling the said means as to cause the resultant current flowing in the delivery circuit to have a fractional frequency operative characteristic to 70 the unmodified current from the said source.

2. The system as set forth in claim 1 comprising a reed operating means energized by current from the said source modified by the said reed operating means. 75

3. In an alternating current system, the combination with a source of alternating current, a current delivery circuit, a reed whose natural periodicity of vibration is different from the periodicity of alternating current 80 from the said source, and operable thereby to vibrate at a rate fractional thereof, current modifying means between the said source and the said circuit, said reed when so vibrated so controlling the said means as 85 to cause the resultant current flowing in the delivery circuit to have a fractional frequency operative characteristic to the unmodified current from the said source, wherein the reed vibration is at a rate fractional to 90 the periodicity of the impressed alternating current in the ratio of 1 to a larger odd number.

4. The alternating current system as in claim 1 comprising reed vibration controlling 95 means operable to cause the vibrating reed to make a slower excursion in one direction from an intermediate position than in the opposite direction, the longer excursion consuming substantially an even multiple of the 100 time consumed in the making of the shorter excursion.

5. In an alternating current system, the combination with a source of alternating current, a current delivery circuit, a reed whose natural periodicity of vibration is different from the periodicity of alternating current from the said source, and operable thereby to vibrate at a rate fractional thereof, current modifying means between the said 105 source and the said circuit, said reed when so vibrated so controlling the said means as to cause the resultant current flowing in the delivery circuit to have a fractional frequency operative characteristic to the unmodified current from the said source, comprising reed vibration controlling means 110 operable to cause the vibrating reed to make a slower excursion in one direction from an intermediate position than in the opposite 115 direction, the longer excursion consuming substantially an even multiple of the time consumed in the making of the shorter excursion, the said reed actuating the said current modifying means when its free end 120 traverses an intermediate point in its path in either direction.

6. In an alternating current system, the combination with a source of alternating current, a current delivery circuit, a reciprocable 125

element whose natural periodicity is different from the periodicity of alternating current from the said source, and operable thereby to reciprocate at a rate fractional thereof, current modifying means between the said source and the said circuit, said reciprocable element when so operated so controlling the said means as to cause the resultant current flowing in the delivery circuit to have a fractional frequency operative characteristic to the unmodified current from the said source.

7. In an alternating current system, a source of alternating current, a reciprocatory type electrical motor, current modifying means operable by the said motor, a service circuit, said modifying means interconnecting the said source and the said circuit, said means being adapted to control the selection of current impulses from the said source, and to transmit the said selected impulses to the said service circuit and to omit a predetermined number of impulses from the said source occurring between selected impulses, the successive selected impulses being of alternate polarity, said motor being operated only by the said selected impulses in the said service circuit.

8. In an alternating current system, the combination with a source of alternating current, a current delivery circuit, a reed whose natural periodicity of vibration is different from the periodicity of alternating current from the said source, and operable thereby to vibrate at a rate fractional thereof, current modifying means between the said source and the said circuit, said reed when so vibrated so controlling the said means as to cause the resultant current flowing in the delivery circuit to have a fractional frequency operative characteristic to the unmodified current from the said source, in combination with an electromagnet for operating the said reed when energized by current from the said source, in combination with circuit connections leading from the current delivery circuit to the said magnet whereby modified current from the said source is delivered to the magnet.

9. In an alternating current system, the combination with a source of alternating current, a current delivery circuit, a reed whose natural periodicity of vibration is different from the periodicity of alternating current from the said source, and operable thereby to vibrate at a rate fractional thereof, current modifying means between the said source and the said circuit, said reed when so vibrated so controlling the said means as to cause the resultant current flowing in the delivery circuit to have a fractional frequency operative characteristic to the unmodified current from the said source in combination with an electromagnet for operating the said reed when energized by current from the said source.

In testimony whereof, I affix my signature.
WILLIAM C. ROE.
